UNITED STATES PATENT OFFICE

2,600,950

MANUALLY PROPELLED VEHICLE

Joseph M. Wyche and Christine A. Wyche,
Dayton, Ohio

Application June 17, 1949, Serial No. 99,698

1 Claim. (Cl. 280—249)

1

The present invention relates to vehicles of the propelled type, particularly to toy wagons, and also to special types of wheel-chairs.

Various forms of hand and foot operated mechanism have been employed in connection with wheel-chairs, bicycles, tricycles, etc., but none of these mechanisms are suitable to the propulsion of a child's wagon in which the total cost must be kept low and all danger from rotating parts must be eliminated. The self-propelling mechanism of the standard types of wheel-chairs is suited to occupants having only specific infirmities so that other patients may not be able to self-propel wheel-chairs that are available on the market.

The primary object of the invention is to provide a toy wagon with self-propelling mechanism of a character in keeping with the low investment in the toy and yet sufficiently sturdy to withstand rough usage by the child.

Another object is to provide a toy wagon of the self-propelled type which presents no danger to the child and can be operated with little or no practice in order to be adaptable to even very young children.

Still another object is to provide a child's four-wheel vehicle with a propelling mechanism which can be operated by a simple hand-wheel or lever at the front end of the vehicle.

Another object is to provide a child's wagon with a hand-operated device for propelling the wagon and for automatically disengaging the device from the wheels when the wagon is coasting.

A still further object is to provide a child's wagon with a combined propelling and braking mechanism in which the brakes can be applied by the same hand-operated device which furnishes the propelling power.

Another object is to provide a child's wagon or similar toy with combined propelling, braking and coasting mechanism, operated through a rotating wheel or lever positioned within convenient reach of the child.

A still further object is to provide a driving and steering mechanism for a child's wagon which can be readily applied to the existing types of carts and no radical changes in design need be made except for the addition of such mechanism.

The final object is to provide a combined hand-operated driving, braking and coasting mechanism which can be readily applied to a child's wagon or to vehicles occupied by adults, as wheel-chairs.

2

Other objects and features will be apparent as the specification is perused in connection with the accompanying drawings in which:

Figure 1 represents a perspective view of a child's wagon of typical size and shape, but provided with the improved propelling and steering mechanism;

Figure 2 is an enlarged fragmentary view, partly in section and partly in elevation, broken 10 away to show perspectively some of the internal parts of the improved mechanism;

Figure 3 is a plan view of the ratchet wheel and associated parts for operating the brake, such view being taken at about the position indicated 15 by the line 3—3 in Figure 5; Figure 3a shows a detailed section of the pivot element used in connection with the pawl mechanism for that wheel;

Figure 4 represents a sectional view taken along line 4—4 in Figure 5, showing the brake drum 20 and the ratchet wheel which drives the ground wheels;

Figure 5 is a transverse sectional view but with some of the parts in elevation for clearness, taken through the propelling mechanism at about a 25 position indicated by the line 5—5 in Figure 1, looking at the end of the cart.

Referring to Figs. 1 and 2, reference character 1 designates generally the chassis of a child's wagon of standard construction, including floor boards 2, tongued sides 3 and ends 4. A seat 5 having cleats 6 may be provided, this seat being adapted to slide along the top edge of the side members 3. To the rear of the chassis there is a fairly deep body 7 to simulate a delivery wagon 35 and held in position by wooden uprights 8 which are slidably received in brackets 9. In order to give the chassis greater rigidity and to furnish a surface from which the various mechanisms can be suspended, a metal sheet 10 may be screwed 40 or otherwise secured to the floor 2.

The chassis is mounted on two sets of wheels 11, 12, of which the details are shown in Fig. 5, and are preferably rubber-tired. The rear wheels 11 are carried on a rod 13 which does not 45 rotate but is swivelly mounted (not shown) in the floor board 2 and plate 10, midway of the width of the cart, so that the wheels may be swung in the horizontal direction for steering purposes. Any suitable system of levers or 50 mechanisms can be provided for moving the rod 13 about its vertical mount and as illustrated, we show a downwardly extending vertical bar 14 slotted as at 15 along its length to loosely receive the rod 13 at the lower end and pivoted at 55 the position 16 to the plate 10.

There is a long horizontal bar 17 provided with a pin 18 contained within the slot 15 and the forward end of this bar is pivotally attached to the lower end of a lever 19. The latter is swingably mounted at the pivot 20 attached to the side of the cart and this lever terminates in a handle or grip 21. Thus, when the child pulls back on the handle 21, the left-hand wheel 11 seen in Fig. 1, will tend to move forward and the right-hand wheel 11 (not shown) will move rearward, causing the front end or nose of the cart to swerve to the right. An opposite movement of the handle 21 will cause the cart to swing to the left so that complete steerage of the vehicle is conveniently obtained in this manner.

By positioning the steering mechanism at the rear set of wheels instead of at the front set, the latter is left entirely free to receive the improved propelling, coasting and braking mechanism, which will now be described, in a position that is most convenient to the child driver.

A vertical driving rod 22 is loosely received by an opening in the floor board 2 and the plate 10, this rod being provided at its upper end with a wheel 23 provided with a hand-grip 24. The rod 22 is held in its proper vertical position by means of a flanged bushing 25 which slidably receives the rod and supports a collar 26 which is pinned or screwed as indicated at 27 to the rod. A similar collar 28 is carried by the rod and abuts the metal plate 10, this collar also being pinned or otherwise secured to the rod as indicated at 29. Thus the entire downward thrust of the rod is accommodated by the surface between the collar 26 and the upper edge of the bushing 25.

The combined propelling, braking and coasting mechanism is carried on a metal cradle as shown in Figs. 2 and 5 and supported at each end by angle iron members 30 (Fig. 5) to which is attached a pair of metal uprights 31 serving as a frame for the front axle. The latter includes a pair of tubular members 32, the inner ends of which are inserted in a completely enclosed metal box or compartment 33 directly under the rod or shaft 22. The outer ends of the tubular member 32 are plugged as indicated at 34 rotatably to receive a rod or shaft 35 constituting the front axle.

Spun metal wheels 36 may be attached to the axle 35 and held in position by a thick washer 37 and a cotter pin 38. A cap 39 may be provided over the washer and secured thereto in any suitable manner, for example by means of a threaded aperture 40 for threadedly engaging the ends of the axle. The cap is desirable to prevent any accidental contact by the child with the spinning cotter pin 38. It also has ornamental purposes.

The rear wheels 11 may be secured to the axle 13 by an arrangement such as has been shown and described in connection with Fig. 5. The periphery of the spun wheels 36 may be caused to curve outwardly as indicated at 41 to leave a seat for a solid rubber tire 42.

The front axle 35 and the wheels 36 are given a rotary movement by means of a pair of intermeshing gears 43, 44 contained within the housing 33. Gear 43 is pinned to the axle 35 as indicated at 45 and the gear 44 is pinned as indicated at 46 to the vertical shaft 47. The latter is positioned directly in line with the shaft 22 but is separate from that shaft as will be explained in connection with the remainder of the mechanism.

The left-hand angle iron 30 as seen looking into the front end of the cart is provided with two horizontal rods 48 extending inwardly toward the middle of the cart. These rods loosely receive a vertical plate 49 and there is a compression spring 50 interposed between the inner vertical surface of the angle iron and the immediately adjacent surface of the plate. The plate is therefore permitted to move in the horizontal direction along the rods 48 and against the compression spring. The plate 49 is provided with an integral horizontally extending shelf or ledge 51 which serves as a support for a pawl 52. This pawl is swingably mounted on the ledge 51 by means of a stud 53 which is threaded as indicated at 54 into the ledge.

The pawl 52 is backed by a compression spring 55 contained in a box 56 which is secured to the ledge 51 and a stop pin 57 is provided to prevent any excessive lateral movement of the pawl. The end of the pawl is given any suitable shape so as to fit into the teeth of a ratchet wheel 58 which is provided with a hub 59 pinned to the shaft 22. Consequently, as the wheel 23 is rotated in the counter-clockwise direction, one of the teeth of the ratchet wheel will exert a pressure on the end of the pawl 52 and cause the plate 49 to move along its rod supports 48 against the spring 50. The spring 55 serves to cause a firm contact between the pawl and the ratchet tooth.

At the lower end of the plate 49 there is a rod 60, this rod having a threaded end to pass loosely through a metal plate 61 to which it is secured by a nut 62. This plate is pivotally mounted on a long pin 63 which passes through a pair of metal blocks 64 secured as by welding to the plate 10. The plate 61 is provided with an inwardly extending projection 65 on which is mounted an asbestos brake shoe 66.

There is a brake drum 67 cooperating with the shoe 66, this drum being adapted to rotate when the driving wheel 23 is turned or when the ground wheels 12 are rotated and the cart is operated under coasting conditions. Thus when the wheel 23 is given a short counter-clockwise movement to cause the plate 49 to move to the left, as explained hereinbefore, the plate 61 will swing about the pivot rod 63 and cause the shoe 66 to come into close contact with the brake drum 67. The harder the wheel 23 is pulled counter-clockwise, the greater will be this braking effect at the drum so that the child has the wagon under complete control at all times.

In addition to the ratchet wheel 58, there is a second ratchet wheel 68 pinned as at 69 to the shaft 22. The teeth of the ratchet wheel 68 are directed oppositely from the teeth in the ratchet wheel 58 as can be readily seen in Fig. 2. A pawl 70 is swivelly mounted at 71 on a web 72 which extends across the lower edge of the brake drum 67. This web terminates at the center in a hub 73 which is pinned as at 74 to the shaft 47 and loosely receives the lower end of the shaft 22. Thus the hub serves as a rotating bearing for the shaft 22 and also as a horizontal support for the lower surface of the ratchet wheel 68. As shown in Fig. 4, a spring 75 contained in a spring box 76 bears against the pawl 70 to assure firm contact with one of the teeth of the ratchet wheel 68.

For driving the wagon, the wheel 23 is rotated by the handle 24 and if this rotation is in the clockwise direction, it is obvious that the pawl

52 is not given a leftward motion (as seen in Fig. 2) but instead the ratchet wheel 58 simply clicks in a harmless manner. But the rotation of the shaft 22 causes the ratchet wheel 68 to rotate and applies a pushing force to the pawl 70. Since this pawl is secured to the web 72, the latter and the brake drum 67 are caused to rotate at the same speed as the ratchet 68 and the shaft 22. The web 72, in being given a clockwise rotation, causes the hub 73 to rotate and since the latter is pinned to the shaft 47, the gear 44 is rotated to drive the wheels 33.

Assuming now that the wagon is traveling down a steep hill so that no energy is required for rotating the wheel 23. Instead of permitting this wheel to be driven by the ground wheels which now become the drivers, we have provided a novel and inexpensive mechanism for permitting the wagon to free-wheel or coast. The rotating power at the ground wheels is carried through the gears 43, 44 to the shaft 47 and thence to the brake drum 67. The latter is now traveling in such a direction as to pull the pawl 70 away from the teeth of the ratchet wheel 68 and the latter does not turn, but only a harmless click is caused. The wheel 23 therefore remains stationary and becomes free from danger even to the youngest child operator.

It will be noted that the braking surface 67 rotates in the same direction when coasting as when being driven by the wheel 23 so that there is no sudden shock to the child in passing from a driving to a coasting condition, as it simply means that the child has chosen not to rotate the driving wheel 23.

If the wagon attains too fast a speed for safety of the child, it is simply necessary for him to pull back on the wheel 23, i. e. move the wheel in the counter-clockwise direction, at which time the brake shoe 66 will be firmly applied against the drum 67 to stop the wagon. Any degree of a braking effect may be obtained since the movement of the pawl 52 in the left-hand direction is gradual, depending on the amount of movement of the wheel 23 as shown in Fig. 3. Consequently, the child is not apt to stop so quickly as to be thrown forward.

It has been explained that the wagon is steered preferably from the rear axle by swinging the latter about a vertical pivot and operable at the handle 21. Consequently, a child would have no difficulty in mastering the combined operation of the driving wheel 23 and the steering handle 21. By placing the combined propelling, coasting and braking mechanism on the front axle, considerable complications and expense are eliminated since there is no need for a drive shaft running back to the rear axle.

It will be further noted that the gears 43, 44 are contained in a complete enclosure which not only prevents access of a child's finger, but also, if desired, may contain a lubricant. In this case it may be desirable to plug up, as indicated at 77, the adjacent inner ends of the tubular member 32 so as to keep the oil within the box 33, in which case these plugs assist in preventing any whip of the axle 35. The rigidity with which the box 33 is held in position, particularly when the plugs 77 are employed to support the axle,

may be enhanced by the use of ribs 78 which extend between the box and inside surface of the uprights 31 to which they may be welded.

While we have shown and described the gearing 43, 44 as constituting two spur gears in mesh, it is evident that if desired a conventional differential mechanism may be employed at this position in order to facilitate the movement of the wagon around sharp corners. However, in general, we have found that the two-gear mechanism is sufficient to negotiate most corners and such mechanism is preferred in view of its simplicity and inexpensiveness.

It is obvious that in order still further to protect the mechanism from the accidental insertion of a child's hand, all of the mechanism including the ratchet wheels 58, 68 and the brake drum 67, may be enclosed by means of a housing (not shown) secured in any suitable manner to the uprights or the angle irons 30.

While we have described our invention as pertaining more particularly to a child's wagon, it will be understood that the mechanism would lend itself to vehicles that are occupied by adults and for any purpose, particularly in the case of wheel-chairs in which the occupant is unable to operate a side drive lever or to turn the circular hand-grip attached to one of the large front wheels.

It will be understood that various modifications and arrangements in structure could be made without departing from the spirit of our invention and, accordingly, we desire to comprehend such modifications and substitutions of equivalents as may be considered to come within the scope of the appended claim.

Having thus fully described our invention, what we claim as new and desire to secure by Letters Patent, is:

A wagon comprising a chassis mounted on wheels, forward and rear, means for driving, coasting and braking the forward wheels, said means comprising a shaft extending upwardly from the chassis and carrying a pair of ratchet wheels, the teeth of which are arranged in opposite directions, one of the ratchet wheels operating through a pawl and movable plate mechanism for applying a braking effect to the forward wheels acting as a driver, and the other ratchet wheel operating through a pawl and an attached plate for driving the front wheels in the forward direction when the shaft is rotating, but permitting a disconnection of this other ratchet wheel when the front wheels become the driver and the last mentioned ratchet wheel is held stationary.
